Atty.

UNITED STATES PATENT OFFICE.

CEDRIC HAROLD HANWELL, OF NORTHAMPTON, ENGLAND.

TOY CANNON, PISTOL, GUN, AND THE LIKE.

Application filed January 29, 1923. Serial No. 615,728.

To all whom it may concern:

Be it known that I, CEDRIC HAROLD HANWELL, a subject of the King of Great Britain, residing at Northampton, England, have invented certain new and useful Improvements in Toy Cannons, Pistols, Guns, and the like, of which the following is a specification.

My invention relates to toy cannons, pistols, guns and the like, of the type in which the propulsion of the projectile is effected by the ignition of a combustible mixture.

My invention has for its object to provide a toy of the type indicated above, in which the loading and firing is effected in an improved manner.

My invention consists in a toy of the type indicated in which the propellant is introduced into a firing chamber, disposed in the breech of the gun, the firing chamber being provided with vents communicating with the barrel chamber containing the projectile.

My invention further consists in the improved toys to be hereinafter described.

Referring now to the accompanying drawings which illustrate my invention, and form part of my specification,

Figure 1 shows a plan and Figure 2 shows an elevation of one form of my invention, while

Figure 3 shows a sectional elevation.

Figures 4 and 5 show detail sectional and end elevations respectively of the firing chamber.

In carrying my invention into effect according to one form, and as applied by way of example to a toy cannon, using a match of the "Swan vesta" type of ammunition, I form a barrel 1, Figures 1, 2 and 3, with a small bore for the greater portion of its length and an enlarged bore in the breech portion.

In the enlarged breech portion a firing chamber 2 is introduced which has inclined ducts 3, Figures 4 and 5, formed therein for allowing the explosion gases to pass from the firing chamber into the barrel portion and expel the projectile 4.

A hole 5 is provided in the forward end of the firing chamber to allow the match head to be ejected after firing by means of a ram rod.

To the rear of the match head a pointed striker 6 is disposed, which is adapted to be forced forward when desired by releasing a

trigger 7, rotatably mounted on the pivot 8, attached to the gun carriage.

The forward ends of the springs 9 are connected to the pin 10 on the trigger 7, the rear ends of the springs being connected to a pin 11 on the gun carriage.

The arrangement of the springs and trigger is such that when the latter is withdrawn to the retracted position, the line of action of the springs pass through or over the centre of the pivot 8, of the trigger so that the latter remains in this position.

The cannon is mounted on wheels 12 and the carriage is provided with an elevating screw 13.

In order to load the cannon the head of a match is cut off from the stem, and inserted with its dipped end outwards in the firing chamber 2.

The striker 6 is next inserted in the firing chamber, and these parts are then inserted in the breech. The trigger 7, is made to contact gently with the striker and pressure exerted on the trigger to compress the charge in the firing chamber. The severed stem of the match is then inserted from the muzzle end, and forms the projectile.

To fire the cannon, the trigger 7 is retracted and released when it is forced forward by the springs, so as to contact sharply with the striker and fire the match head in the firing chamber.

The gases of explosion issuing through the vents 3 cause the match stem to be projected with a force sufficient to carry it for distances ranging from 20 to 30 feet.

In some cases instead of using matches of the above type, matches of the safety type may be used. In such cases, the bore of the firing chamber is lined with a piece of paper or other material, prepared so as to cause ignition of the match head when in rubbing contact therewith.

The match head when using safety matches is not initially compressed as above described, and is fired by rubbing against the lining of the chamber as it is driven forward by the striker.

Again, in other cases I may use any suitable form of explosive mixture instead of a match head in which case the hole 5 in the inner end of the firing chamber would be dispensed with as it would not be necessary to use a ram rod to dislodge the residue.

Although I have described my invention

by way of example as applied to a cannon it will be evident that it may also be readily applied to toy pistols, guns or the like.

By means of my invention it will be seen that a toy cannon, pistol or gun is provided which may be loaded and fired in a safe and expeditious manner.

I claim:

1. In a toy cannon, the combination of a carriage, a barrel mounted on the carriage and having the breech portion of larger bore than the front portion thereof, a removable firing chamber in said breech portion, said firing chamber having a restricted opening 15 at its forward end with ducts intercepting said restricted opening and communicating with said front portion, a pin in the firing chamber, and striking means engaging the pin for igniting a propellant in said firing 20 chamber.
2. In combination a barrel having the breech portion of larger bore than the front portion thereof, a removable firing chamber adapted to be inserted longitudinally in said 25 breech portion, said firing chamber being formed with ducts to establish communication between the interior of said chamber and the front portion of the barrel around the charge in said firing chamber, said front 30 portion together with striker means operative in and for igniting a propellant in said firing chamber, as set forth.
3. In combination, a barrel having the breech portion of larger bore than the front 35 portion thereof, a removable firing chamber in said breech portion having ducts communicating with said front portion, striker pin disposed in said firing chamber, a carriage for said barrel, together with trigger 40 means mounted on said carriage, and co-acting with said striker pin to ignite a propellant in said firing chamber as set forth.
4. In combination, a barrel having a breech portion adapted to receive a propellant charge therein and provided with duct 45 means arranged laterally of the charge space and communicating with said barrel portion, wholly beyond said propellant, together

with means for igniting a propellant in said breech portion, substantially as described.

5. In combination, a barrel having a breech with a restricted opening at its forward end, and duct means communicating with and arranged laterally of said restricted opening and communicating with the front portion of said barrel together with means for igniting a propellant in said breech portion.

6. In combination, a barrel having a breech portion of larger bore than the front portion, a firing chamber in said breech portion and having a restricted opening at its forward end with duct means communicating with and arranged laterally of said restricted opening and communicating with said front portion together with means for igniting a propellant in said firing chamber.

7. In combination, a barrel having a breech portion of larger bore than the front portion, a removable firing chamber in said breech portion and having a restricted opening at its forward end with duct means communicating with and arranged laterally of said restricted opening and communicating with said front portion, together with means for igniting a propellant in said breech portion.

8. In combination, a barrel having an enlarged breech portion to receive a charge, means for compressing the charge in said breech portion, said breech portion being formed with a plurality of openings to establish communication between the barrel and enlarged breech portion, said openings being arranged radially of and wholly beyond the charge receiving space.

9. In combination with a barrel enlarged to form a charge receiving space, of means whereby said space is at all times in open communication with the barrel irrespective of the charge within the space.

In testimony whereof I have signed my name to this specification.

CEDRIC HAROLD HANWELL.
